United States Patent Office

MARTIN LANDENBERGER, OF PHILADELPHIA, PENNSYLVANIA.

Design No. 4,670, dated February 21, 1871.

DESIGN FOR SHAWL.

The Schedule referred to in these Letters Patent and making part of the same.

to all whom it may concern:

Be it known that I, MARTIN LANDENBERGER, of Philadelphia, in the county of Philadelphia and in the state of Pennsylvania, have invented a certain new and useful Design for Shawls; and do hereby declare that the following is a full, clear, and exact description thereof;

reference being had to the accompanying drawing and to the letters of reference marked thereon making a part of this specification.

My design is applied to one-faced shawls, and consists of stripes, forming the border, and bars of silk, different-colored silk and worsted, alternating, as shown, and running at right angles with and on top the border-stripes and ground of the shawl.

By a one-faced shawl I mean a shawl upon which the stripes, figures, &c., are thrown up on one side only, while on the other side they are merely faintly, if at all, discernible.

In the drawing—

A represents the ground-work, and
B, a series of stripes, running parallel with each other, and forming the border.

C C represent other stripes or bars of silk, or different-colored silk and worsted alternating or interchangeable, and running at right angles with and across the stripes B B and the ground A, and flushed or thrown up on the top or surface of said stripes B, as well as on the ground A.

These stripes C C, being of silk or different-colored silk and worsted, alternating or interchangeable, and varying in color, produce a beautiful effect and give a peculiar and distinct character to the design.

What I claim is—

The design for a one-faced striped shawl, as herein described.

In testimony that I claim the foregoing I have hereunto set my hand this 21st day of January, 1871.

MARTIN LANDENBERGER.
